UNITED STATES PATENT OFFICE.

JOHN ILLINGWORTH, OF NEWARK, NEW JERSEY.

INGOT-FORMING APPARATUS.

SPECIFICATION forming part of Letters Patent No. 394,695, dated December 18, 1888.

Application filed August 2, 1887. Serial No. 245,992. (No model.)

To all whom it may concern:

Be it known that I, JOHN ILLINGWORTH, a citizen of the United States, residing at Newark, in the county of Essex and State of New Jersey, have invented certain new and useful Improvements in Ingot-Molds and the Process of Casting Ingots; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of molds for casting ingots shown in cotemporaneous applications for patents serially numbered 240,875 and 241,163, in which the ingot is cast by the successive pouring of molten metal into the top of the mold, the casting being lowered through the open bottom of the mold and thereat broken off into ingots.

The object of the invention is to secure a more perfectly automatic movement of parts, whereby the ingot is cast with greater convenience and rapidity.

The invention consists in the improved ingot-forming apparatus and in the arrangement and combination of parts connected therewith, substantially as will be hereinafter set forth, and finally embodied in the clauses of the claim.

Referring to the accompanying drawings, in which like letters of reference indicate corresponding parts in each of the several figures, Figure 1, Sheet 1, is a front elevation of the improved apparatus. Fig. 2 is a side elevation of the lowering device. Fig. 3 is a plan of a clamp for grasping the ingot in the lowering movement. Figs. 4, 5, 6, and 7 are detail views of certain parts of the lowering mechanism, as will be hereinafter described. Fig. 8, Sheet 2, is a central vertical section taken through the apparatus and lowering device. Fig. 9 is a plan of the head of a hydraulic arm or piston adapted to engage the lower end of the lowered body-casting and break the same into ingots, and Fig. 10 illustrates the under side of the funnel employed in connection with the mold.

In said drawings, *a* indicates a base, frame, or bed, at the top of which is a fulcrumal bearing, *b*, and at the bottom of which is a stop-bed or floor, *c*, adapted to limit the downward movement of the ingot. The fulcrumal bearing is perforated to allow the ingot to pass therethrough, the perforation *d* conforming more or less closely to the size and shape of the ingot. It prevents the ingot from moving laterally to any material extent when the ingot is being broken or severed from the body of the casting, and it prevents said casting from being pivotally turned in the mold during said severing process. Above said bed or frame *a* is arranged the mold *e*, a space about equal to or somewhat greater than the length of the desired ingot being formed between the bottom of the mold and the top of the fulcrumal plate or bearing to allow for the play of a certain reciprocating clamp or grasping device, *f*.

The mold *e* has slightly-tapering interior walls and is preferably provided with an ordinary water-jacket, *g*, of any ordinary construction, adapted to receive water from suitable supply-pipes by any of the means well known in this branch of manufacture. Said jacket may be an integral part of the mold or of separate parts, as in Fig. 8. In the latter case the jacket may be braced, as at *h*³ *h*³, in any suitable manner.

At the upper end of the mold is provided a funnel or feed, *h*, to feed the molten metal down through the center of the mold-chamber, 85 the said funnel or feed being of the usual construction, save that it is provided on the under side thereof, where it rests upon the top of the mold, with a series of air-ducts, *i*. As the molten metal passes through the central 90 perforation, *h*', the air in the mold-chamber *h*² escapes through the ducts *i*, so that no air-bubbles are formed in the flowing metal.

The clamp or grasping device *f*, for lowering the ingot, consists of two arms, *f*' *f*', Figs. 3 95 and 8, which are pivoted or hinged together, as at *f*², near where they grasp the ingot, and at their opposite ends are inclined, as at *f*³, Figs. 2 and 3, and enter into engagement with correspondingly-inclined surfaces, *f*⁴, of a piston or rod, *k*, arranged in connection with a hydraulic cylinder, *F*, of any suitable con-

struction. When the said piston is at the upper limit of its stroke, the arms f' carried thereby are at their upper limit ready to grasp the ingot. A downward movement of the piston causes the inclined sides f^4 of the piston to force the said arms f' together to grasp the ingot, as will be understood.

To secure a more certain engagement and disengagement of the grasping-arms from the ingot and obtain the same automatically, I provide for a resistance to the movement of the arms and the block carrying the same, so as to cause the inclines $f^3 f^4$, above referred to, to co-operate more certainly. To this end I have provided a block or carrier for the grasping-arms, which moves vertically with the grasping-arms and engages certain means, hereinafter described, for obtaining resistance to the movement of said block. Said block n is provided with an aperture, n' , through which the grasping-arms pass, as indicated in Fig. 1, the said aperture extending horizontally to hold the grasping-arms, so that they will extend laterally into engagement with the ingot. Said block is also provided with a horizontal aperture or passage, n^2 , through which the piston k passes. At the corners the block is provided with suitable ways—such as the recesses n^3 —to engage or receive corner-posts or tracks m , between which last the said block slides. The slot n' is large enough to allow to the arms a limited movement to and from one another in releasing or clamping the ingot. To secure the resistance referred to, I have slotted the posts or tracks m —that is, formed chambers or recesses o , Fig. 4, therein. Into the recesses I have arranged repressible bolts p , having rounded ends, which project slightly beyond the inner walls of the posts or tracks m , so as to engage the block n . The said bolts are pressed by a spring, q , and are held in proper operating relation by the nut r , secured upon the shank s of said bolt in any ordinary way.

In the downward motion of the block n at the beginning of the stroke it strikes the bolt p and is retarded thereby, so that greater exertion is required to pass the block below the bolts, so that the inclines f^3 of the arms f' are with certainty caused to press against the corresponding inclines, f^4 , of the piston, and the arms are thus driven together and caused to hug the ingot. Similar repressible bolts are disposed at a lower part of the arms, as at t , so that in the return movement of the block the block will be retarded in a like manner, and the arms will be disengaged with certainty from the inclines of the blocks and will be allowed to separate under the influence of suitable springs, u , Fig. 3, disposed between the arms, and thus released from holding engagement with the ingot. The weight of the block n and the arms f is counterbalanced more or less completely by weights v , suspended from suitable ropes or chains, w^4 , arranged upon pulleys w^5 , Fig. 1.

It will be observed upon reference to Fig.

8 that the piston moves independently to a limited extent in the block n , this movement being sufficient to secure the clamping operation already described; but its movement is limited by stops $k' k'$, so that after the clamping operation is effected the piston will certainly and effectively carry the block with it. To break the ingot from the body-casting 75 with greater convenience, I prefer to arrange the cylinder and piston as shown in Fig. 8, where w indicates a cylinder disposed horizontally nearly in line with the lower end of the casting, and w' is a piston adapted to be 80 projected from said cylinder. Said piston is provided with laterally-extending fingers or bearings u^2 , adapted to engage the opposite sides of the ingot. When the ingot is lowered, the piston is drawn or forced out, so that the said fingers in a vertical position are laterally adjacent to the end of the ingot. The piston is then turned pivotally by hand or other means, so that the said fingers are brought over on opposite sides of the ingot, 85 as in Fig. 8. The water is then turned on and the piston operated reciprocally, so that the ingot is forced backward and then forward with a quick sharp movement, and thus severed from the body-casting quickly and effectively. 95

In carrying out the operation I first arrange a suitable plug or block in the bottom of the mold, preferably provided with a dovetailed recess or projection in the upper end 100 thereof, into which the molten metal can run. Said plug or block closes the lower end of the mold-chamber and projects below the bottom of the mold to allow the grasping-arms f to be secured thereon. The molten metal is then 105 fed to the mold to form the ingot. When the metal is sufficiently set, another quantity equal to the desired ingot is fed to the mold, which will fill or nearly fill the mold. After this has set at its outer part the two united ingots are lowered, so that the first cast portion projects below the bottom of the mold. I may, before the second casting is fed upon the first lower the said first casting a few inches to free it from the sides of the mold, so that in 110 subsequent operations there will be no danger of premature breaking. After lowering the ingot the chamber thus formed in the mold is again filled, so that a heavy body of metal 115 is poured upon the metal partially hardened and before the latter has shrunk at the interior to form the "pipe" or the objectionable flaw or recess. This molten metal last cast flows into the contracted head of the metal previously cast, filling the recess, central aperture, or pipe, which would otherwise remain therein. 120

It will be observed that the filling of the shrinking ingot is effected under a heavy body of molten metal. The process in this respect differs materially from the mere filling of a recess or pipe at the top of an ordinary mold by pouring a quantity of metal into the pipe only sufficient to fill the pipe. 125 130
